UNITED STATES PATENT OFFICE.

AMOS F. DIXON, OF NEWARK, NEW JERSEY, ASSIGNOR, BY MESNE ASSIGNMENTS, TO
WESTERN ELECTRIC COMPANY, INCORPORATED, A CORPORATION OF NEW YORK.

TELEGRAPH SYSTEM.

1,231,140.

Specification of Letters Patent. Patented June 26, 1917.

Application filed April 15, 1915. Serial No. 21,595.

To all whom it may concern:

Be it known that I, AMOS F. DIXON, a citizen of the United States, residing at Newark, in the county of Essex and State 5 of New Jersey, have invented certain new and useful Improvements in Telegraph Systems, of which the following is a full, clear, concise, and exact description.

This invention relates to telegraph systems, more particularly to multiplex printing telegraphs, and its principal object is to provide for automatically signaling the receipt of operative current impulses at any printer.

15 In ordinary telegraphs a galvanometer or other indicating instrument in the line circuit will give a sufficient notification of the receipt of current impulses but in multiplex operation, such an indication is not sufficient.

20 The attendant must be able to determine which printer is at fault. Without some such arrangement an attendant cannot know whether the inaction of a particular printer is due to the non-receipt of operative

25 current impulses or to the failure of the apparatus to properly respond to such impulses. By the use of this invention, however, such uncertainty is obviated and an attendant is notified immediately upon the 30 failure of a printer to respond.

To the above end the invention contemplates an indicating or signaling device associated with each printer and responsive only to impulses operative upon such 35 printer. A signal lamp coöperating with additional segments associated with the receiving segments on the distributers and controlled from the same source as the selecting electromechanisms is believed to be the 40 preferable, although obviously not the only embodiment.

The above and other objects of this invention will be fully set forth in the following description and claims and will be more 45 readily understood by reference to the accompanying drawing, wherein Figure 1 shows the preferred embodiment diagrammatically and Fig. 2 is a partial development of the receiving current distributer.

50 At the transmitting station there is the usual distributer 5 associated with suitable transmitting or current controlling devices for supplying the desired current impulses sequentially to a transmission line L to af-

fect the printing apparatus at the receiving 55 station A. These impulses traverse a polarized relay 10, which may be of the usual well known construction. It is provided with a pivoted armature 11 coöperating with suitable contacts, one of which is connected 60 to a grounded source of energy 12. Armature 11 is connected to a common receiving ring 15 of a receiving current distributor 16. This distributor is made up of several groups of receiving segments 21, 22, 23, 24 65 and 25 (in the drawing four such groups being shown) insulated from each other and adapted to be successively brought into electrical connection with ring 15 by a pair of 70 brushes 30, which are rotatable in the direction of the arrow, in synchronism with the received impulses, by a suitable arm 31. Each of the receiving segments 21 to 25 inclusive may be associated with any desired 75 and appropriate form of selecting apparatus; as, for example, the multiplex printing telegraph receiver disclosed in Patent No. 1,103,133 patented July 14, 1914.

Located between pairs of adjacent receiving segments of a group and insulated therefrom are signal segments 80 35.

These segments are also adapted to be successively connected to ring 15 by brushes 30 and those associated with a given group of receiving segments are connected together 85 and to a signal lamp 36. This lamp is preferably located near its associated printer.

Now when the operative impulses in line L cause polarized relay 10 to connect source 90 12 to ring 15 current will flow through certain receiving segments 21 to 25 inclusive, to the proper selecting apparatus coöperating therewith, as fully described in the above noted patent. The reversals of line current are preferably so timed relative to the movement of arm 31 that they occur when outer brush 30 is approximately at the mid-point of a signal segment. This is clearly shown in Fig. 2, wherein the shaded portion of the representation of the line signals indicates 100 the operative impulses. Therefore, upon each change in the line current which results in armature 11 connecting source 12 to ring 15 a circuit will also be formed through the signal segment 35 upon which the outer brush 30 happens to be at that moment to signal lamp 36, causing the lamp to glow. The attendant is thereby notified that opera- 105

tive signaling impulses are being received in the quadrant or quadrants, whose signal lamps 36 are flashing, and that the printers associated therewith should be functioning. 5 If, however, the printers are not operating during the flashing of the signal lamps, it is at once evident that there is some trouble in the system between the receiving segments and the apparatus for performing the de- 10 sired operation. It will be apparent from the above description and a study of Fig. 2 that, even though arm 31 is not rotating so that the current reversals take place when outer brush 30 is at the mid point of a sig- 15 nal segment 35, a circuit may still be established between signal 36 and source 12 which should be sufficient to cause the lamp to glow. The more beyond the mid point the outer brush 30 is at the time of a re- 20 versal to an operative impulse, the shorter will be the period of flow of current from source 12 if the preceding impulse was inoperative. While if the reversal takes place before the mid point is reached the flow of 25 current under such a condition will be for a longer period.

What is claimed is:

1. In a telegraph system, the combination of a current distributor having receiving segments divided into groups, signal segments positioned between said receiving segments, and a signal coöperating with the signal segments associated with a group of receiving segments. 30
2. In a telegraph system, the combination of a current distributor having receiving segments divided into groups, signal segments associated with each of said groups, means controlled by line impulses for supplying current to said segments, and a plurality of signals, one associated with the signal segments of each group and operable by the current thus supplied thereto. 35
3. In a telegraph system, the combination of a current distributor having receiving segments, signal segments associated therewith, and a signaling device coöperating with said signal segments and responsive to reversals of line current. 45

In witness whereof, I hereunto subscribe my name this 14th day of April A. D., 1915.

AMOS F. DIXON.
